UNITED STATES PATENT OFFICE

168,298

TABLE LAMP

Joseph Guy, Quebec, Quebec, Canada

Application October 19, 1951, Serial No. 17,020

Term of patent 14 years

(Cl. D48—20)

To all whom it may concern:

Be it known that I, Joseph Guy, a citizen of Canada and a resident of the city of Quebec, Province of Quebec, Canada, have invented a new, original, and ornamental Design for Table Lamp, of which the following is a specification, reference being had to the accompanying drawing, forming a part thereof.

I claim:

The ornamental design for a table lamp, as shown.

JOSEPH GUY.
